UNITED STATES PATENT OFFICE

150,669

DESIGN FOR AN ORGAN TONE
CABINET CASING

Victor I. Zuck, Kenmore, N. Y., assignor to The
Rudolph Wurlitzer Company, North Tonawanda, N. Y., a corporation of Ohio

Application June 27, 1947, Serial No. 139,959

Term of patent 7 years

(Cl. D56—4)

To all whom it may concern:

Be it known that I, Victor I. Zuck, a citizen of the United States, residing at Kenmore, Erie County, New York, have invented a new, original, and ornamental Design for an Organ Tone Cabinet Casing, of which the following is a specification, reference being had to the accompanying drawing, forming a part thereof.

Fig. 1 is a front view of an organ tone cabinet casing showing my new design; and

Fig. 2 is a side view thereof.

The dotted line showings in the drawing figures are for illustrative purposes only.

I claim:

The ornamental design for an organ tone cabinet casing, substantially as shown and described.

VICTOR I. ZUCK.
